UNITED STATES PATENT OFFICE.

HOMER ROY FISHEL, OF RALEIGH, NORTH CAROLINA.

COLLAR.

1,128,433.

Specification of Letters Patent. Patented Feb. 16, 1915.

Application filed November 25, 1913. Serial No. 802,990.

To all whom it may concern:

Be it known that I, HOMER ROY FISHEL, a citizen of the United States, residing at Raleigh, in the county of Wake and State 5 of North Carolina, have invented certain new and useful Improvements in Collars, of which the following is a specification.

My invention relates to shirt collars and has for its object the provision of a collar of 10 such construction that a tie may be easily and quickly combined therewith so as to present an attractive appearance and the necessity of passing the tie entirely around the neck of the wearer will be obviated. 15 This stated object and such other objects as will incidently appear from the following description are attained in a device of the character illustrated in the accompanying drawings, and the invention consists in certain 20 novel features which will be particularly pointed out in the claim.

In the annexed drawings: Figure 1 is a perspective view of a collar having my invention applied thereto. Fig. 2 is a perspective view of the tie shown in Fig. 1, looking at the rear side thereof.

The collar 1 may be formed as a part of the shirt or may be detachable as preferred and may be a stiff collar or a soft collar and 30 is equally adapted for ladies' shirtwaists and men's shirts. In the drawings, the collar is shown as a fold collar having its ends meeting at the front, and adjacent the meeting ends I form a plurality of slots 3 which 35 extend parallel with the said meeting ends and are spaced at regular intervals at both sides of the said ends. Any desired number of these slots may be provided, it being understood, of course, that the same number 40 of slots must be provided at each end and that the slots are so located as to constitute pairs.

I employ attaching plates or hooks 5 which may be of light sheet metal, nickel-plated to have a neat finish and prevent 45 rusting of the collar, the said attaching plates being doubled on themselves to provide the inner lips or hooks 6 adapted to pass through the slots and engage against 50 the under face of the outer fold of the collar. The outer member of these attaching

plates 7 is provided with a longitudinal slot 8 through which the fabric strap or band 9 is inserted, the ends of said fabric strap or band being sewed or otherwise secured to the 55 band, as shown clearly in Fig. 2. I prefer to employ elastic webbing for these straps or bands 9, as such material will hold the ends of the collar together and at the same time will permit the collar to yield to the 60 movements of the wearer in turning his head, so that binding of the collar around the neck will be obviated. It will, of course, be understood that any desired number of these connecting bands may be employed 65 and to impart a finished and dressy appearance to the collar I secure upon the outer face of the lowermost band a bow 10, as shown.

My device is exceedingly simple in the 70 construction and arrangement of its parts, may be rapidly adjusted, and will hold the collar in its proper position without causing any discomfort to the wearer. The fastening or unfastening of the collar is not impeded by the application thereto of my invention and it may sometimes be found convenient and even desirable to dispense with the usual collar buttons and rely solely upon the connecting bands to hold the ends of the 80 collar together, as well as to hold the collar in place upon the neck. This is particularly true when the collar is formed on the shirt.

Having thus described my invention, what I claim as new, is:

The combination of a collar provided with 85 pairs of slots adjacent its meeting ends, said slots being parallel with the said ends and the members of each pair being at opposite sides of the ends, connecting bands extending 90 across the meeting ends of the collar, and attaching hooks passing through said slots to engage the inner surface of the collar adjacent the slots and provided in their outer portions with slots to receive the ends 95 of the connecting bands.

In testimony whereof I affix my signature in presence of two witnesses.

H. ROY FISHEL. [L. s.]
